UNITED STATES PATENT OFFICE

FREDERICK L. BRIGHAM, OF SYRACUSE, NEW YORK.

DESIGN FOR A BADGE.

SPECIFICATION forming part of Design No. 23,007, dated January 16, 1894.

Application filed November 1, 1893. Serial No. 489,759. Term of patent 7 years.

To all whom it may concern:

Be it known that I, FREDERICK L. BRIGHAM, of Syracuse, in the county of Onondaga, in the State of New York, have invented a new and useful Design for Badges, of which the following, taken in connection with the accompanying drawing, is a full, clear, and exact description.

The figure is a face view of a badge embodying my design.

The leading feature of my design consists of an angular background or body A, the representation of an open book B on the background having an outline comprising straight and curved lines $b^1 b^2 b^3 b^4 b^5 b^6 b^7$, and the representation of an unfurled flag C upon the representation of the open book, having a substantially rectangular outline comprising straight lines $c^1 c^2 c^3$ and slightly curved lines $c^4 c^5$ disposed respectively in planes arranged obliquely and substantially parallel with the lines $b^1 b^2, b^3$.

The lines $b^1 b^2$ represent the outer edges of the opened leaves; the lines b^2 and b^3 , the bottom edge of the cover, and the division line of the leaves; the curved lines $b^4 b^5$, the top and bottom edges of the open leaves; and the

curved lines $b^6 b^7$, respectively the back of the book and the corners of the leaves. The line c^1 is of greater length than the combined length of the lines c^2 and represents the flag pole of the unfurled flag; and the lines c^3 represent the outer ends or edges of the bars c^4 of the flag.

The lines $c^2 c^3$ represent the upper and lower edges of the flag, and the lines $c^5 c^6$ arranged at an angle with each other and the adjacent ends of the lines $c^4 c^5$ represent an angular panel having a series of stars c^7 arranged thereon in rows parallel with the lines $c^2 c^3$.

A badge embodying this design is highly pleasing and attractive in appearance.

What I claim is—

The design for a badge, substantially as herein shown and described.

In testimony whereof I have hereunto signed my name, in the presence of two attesting witnesses, at Syracuse, in the county of Onondaga, in the State of New York, this 11th day of August, 1893.

FREDERICK L. BRIGHAM.

Witnesses:

CLARK H. NORTON,
E. A. WEISBURG.
